UNITED STATES PATENT OFFICE.

FREDERICK A. GUILLETTE, OF TAUNTON, MASSACHUSETTS.

SELF-THREADING SHUTTLE.

1,184,640.

Specification of Letters Patent. Patented May 23, 1916.

Application filed October 8, 1915. Serial No. 54,812.

To all whom it may concern:

Be it known that I, FREDERICK A. GUILLETTE, a citizen of the United States, residing at Taunton, in the county of Bristol and State of Massachusetts, have invented new and useful Improvements in Self- Threading Shuttles, of which the following is a specification.

This invention relates to self threading or hand threading shuttles and it consists in the novel features hereinafter described and claimed.

An object of the invention is to provide a shuttle of simple and practical structure having means for facilitating the threading thereof and also means for maintaining the thread or filling at a proper tension.

The threading device comprises a plate and means for securing the same in position at the end of the slot of the shuttle, the said plate being provided at a point approximately in alinement with the axis of the spindle with an eye and having a slot leading from the edge of the plate into the eye. The plate is provided at its lower portion with an arcuate curl and the said curl extends through the side of the shuttle when the plate is in position in the slot thereof. The plate is provided with an edge which is inclined from the upper end of the plate toward the outer end of the curl whereby the thread is directed toward the end of the curl as it is slipped along the slot in the plate toward the eye. Partitions are provided in the curl between the eye and the outlet end thereof and the said partitions are located at the opposite sides of the curl and a friction or tension member is located in the curl between the said partitions. The said friction member is substantially cylindrical and is provided at one end with a point which is disposed toward the said eye. By pointing the end of the said friction member, the thread or filling which is knotted may freely pass by the said friction member and under the same while the shuttle is in use.

In the accompanying drawing:—Figure 1 is a top plan view of the shuttle showing the threading device applied. Figs. 2 to 5 are detailed views of the invention.

The shuttle 1 is of the usual configuration and is provided with a longitudinally disposed slot 2. The filling spindle 3 is mounted in the slot 2 in the usual manner and the thread or filling is wound about the said

spindle. The threading device comprises a plate 4, preferably of sheet metal, which is positioned at one end of the slot 2 and which may be secured in the shuttle by means of a screw 5 or other suitable securing device. The plate 4 is provided at a point approximately in alinement with the axis of the spindle 3 with an eye 6 of arcuate configuration. A slot 7 leads from the upper edge portion of the plate 4 into the upper part of the eye 6. At its upper end, the slot 7 is enlarged, as at 8.

The plate 4 is provided at its lower portion with an arcuate curl 9 which in transverse section describes approximately three quarters of a circle. The upper inner edge of the curl 9 is spaced from the under surface of the plate 4. When the plate 4 is in position at the end of the slot 2 in the body 10 of the shuttle 1 one end of the curl 9 passes through the side of the shuttle and terminates approximately at the outer surface of the body of the shuttle. The plate 4 is provided at its upper outer portion with an edge 10 which is inclined from the upper portion of the plate toward the outer end of the curl 9. Partitions are located in the curl 9 between the eye 6 and the delivering end of the said curl, and the said partitions are located at the opposite sides of the said curl. The partitions 11 are approximately semi-circular in side elevation and the straight edges of the said partitions are approximately vertically disposed when the shuttle is in operation in a loom. A tension member 12 is located in the curl 9 between the partitions 11 and the said tension member is approximately cylindrical in form. The tension member 12 is provided at that end which is nearest the eye 6 with a point 13 and the said point is disposed toward the said eye 6.

To thread the shuttle, the thread is led from the winding upon the spindle 3 and caught around the upper edge of the plate 4. The free end of the thread is then drawn in a direction toward the spindle 3 whereby the thread passes down through the slot 7 and enters the eye. The thread also passes down along the edge 10 to the outer end of the curl 9 where it may be engaged by the finger or thumb and drawn through the side of the shuttle 1. As the thread passes down along the slot 7 and the edge 10 of the plate 4, the part of the thread between the said slot and edge passes down along the straight

edges of the partitions 11 and around and under the tensioning member 12. The member 12 normally lies upon the part of the thread which is located between the partitions 11. Inasmuch as the tensioning member 12 is provided with a pointed end 13, should the thread or filling have a knot, the knot is directed by the said pointed end 13 under the tensioning member 12 and the presence of the knot in the thread or filling does not prevent the same from moving freely under the tensioning member 12. The tensioning member is made of metal and consequently is sufficiently heavy to prevent the thread from looping between the delivery ends of the curl 9 and the spindle 3 when the shuttle is in operation in the loom.

In some States, for instance the State of Massachusetts, there are laws preventing the threading of a shuttle by creating suction through the side of the same with the mouth. These laws are made and enforced for sanitary reasons and by the use of the present invention, the shuttle may be quickly threaded without necessitating an operator to create suction through the side of the shuttle with the mouth. By the use of the present invention, the body of the shuttle is not mutilated or damaged by cutting and boring hence the use of the device is an advantage to the owner of the shuttle.

The present device is an advantage to the weaver for the reason that it will not break the warp yarn or unthread while running or in operation.

The use of the present device effects a saving to the loom fixer in that the application of flannel, or felt for tensioning the thread is eliminated and the body of the shuttle is not damaged by tacking the material to the same. The present device is also

of advantage to the shuttle maker in that it saves time in the manufacture of the shuttle and the device may be easily and quickly applied to the body of the shuttle.

From the above description taken in conjunction with the accompanying drawing it will be seen that a self threading, or hand threading device of simple and durable structure is provided and that the same may be easily and quickly applied to the body of a shuttle and when applied may be easily and quickly used for accomplishing the proper threading of the shuttle and while the shuttle is in use the thread is maintained at a proper degree of tension and may move freely through the device notwithstanding that the thread may have knots or other obstruction upon the same.

Having described the invention what is claimed is:

1. A shuttle comprising a body, a curl provided at the edge thereof, spaced partitions located in the curl at the opposite sides thereof, and a tensioning member loosely mounted in the curl between the said partitions, said member being pointed at one end.

2. A shuttle comprising a body, a thread guiding plate attached to the body and having an eye with a slot leading from the edge of the plate into the eye, the plate being provided at one edge with a curl, spaced partitions located in the curl, and a tensioning member loosely mounted in the curl between the said partitions.

In testimony whereof I affix my signature in presence of two witnesses.

FREDERICK A. GUILLETTE.
